UNITED STATES PATENT OFFICE

ORVILLE U. DESHA, OF FORT COLLINS, COLORADO, ASSIGNOR OF ONE-FIFTH TO THE
DESHA TYPELEX TRUST ESTATE, OF FORT COLLINS, COLORADO

KEY ACTION FOR TYPEWRITERS AND OTHER MACHINES

Application filed January 27, 1928. Serial No. 249,880.

In regard to certain more specific features thereof, my invention relates to improvements in the associated and coacting parts of a key mechanism of a machine whose actuating means operatively connecting the type bar and key lever move the type bar to the printing point upon depression of the key lever; said connection embodying coacting means reversely breaking the said connection after the printing impact of the type bar for the return of the type bar to its normal position while the key lever is in depressed position, and also including coacting means for restoring said connection to normal operative position upon release of the key lever; this broad object being the subject matter of an application filed by me on November 5th, 1923, Serial No. 672,871, upon which Patent 1,643,203 issued Sept. 20, 1927, as a contradistinction between previous devices comprising a detachable connection or gap at some point between the key lever and type bar after the latter has been given the movement necessary to effect the printing and before the key lever has completed its cycle of movement.

Among the objects of the present invention, the applicant has endeavored: First, to improve the coacting parts between the key lever and type bar which will provide, among other features, a key action which will be efficient in use, rapid, reliable and silent in operation, and which shall have a light touch for operating the type bars, and reduce the liability of the type to collide or "pile" when operated at high speed. Second. To provide a key mechanism of the above character having few parts simple in construction which will be cheap to manufacture, convenient and easy to arrange and assemble compactly, and construct a key mechanism as to be but little likely to get out of order in usual operation.

My invention, accordingly, consists in certain combinations of elements, features of construction, and arrangement of parts, that may readily be incorporated in certain type-writing machines with only slight modification of the structural features of said machines as they now exist, exemplified in the construction hereinafter set forth, which will be more readily understood from an inspec-

tion of the accompanying two sheets of drawings and the following specification, the scope of the invention, being indicated in the appended claims.

My invention is especially applicable to the usual hand operating machine, as distinguished from a motor driven machine, and is shown in the present case embodied in a machine similar to the Royal standard typewriter. It should be understood, however, that the invention is not restricted to use in a machine of this type, but may be employed wherever found available.

The applicant has endeavored to disclose and describe the construction of the mechanism and manner of its operation and its use in language comprehensible to those versed or skilled in the art who would make or use the device, sufficient to satisfy the requisites of this application, without enumerating every obvious object which is cured or ameliorated by his improvement over the present state of the art, the following being a brief description of the several views of the drawings: Fig. I is a sectional elevation of a type-writing machine taken longitudinally and about centrally thereof, constructed in accordance with my invention and showing elements of one key action only in normal position, and also showing so much of the usual mechanism of the machine as is necessary to illustrate how my invention may be embodied therein. Fig. II, represents a view of the key action similar to Fig. I, the key lever being shown depressed and responding the type bar. Fig. III is a key mechanism similar to Fig. I, the key lever being shown in a depressed position and the type bar responded to printing position. Fig. IV is also a key mechanism similar to Fig. I, the key lever being shown in a depressed position and the type bar returned to its initial position. In this manner the key lever may be held down to its limit of movement and the type bar will complete its incident of response to effect the printing and move out of engagement with the platen and complete its cycle of movement regardless of whether or not the key lever is released, thus relieving the key lever of work during the im- part printing operation.

The following detailed description sets forth the best mode in which the applicant has contemplated applying the invention. It is understood, of course, that for the sake of clearness and to avoid complication of drawings, elements of the complete machine already known to the art, constituting no part of the present invention, and statements of mere obvious facts, are omitted. In the accompanying drawings similar reference characters indicate corresponding parts in the several views and in order to facilitate observance of a clear distinction between this and copending applications, the reference characters also indicate, as far as practical, the corresponding parts in the several views of my copending applications, Serial No. 55,227 filed September 8, 1925 and Serial Nos. 178,083, 178,084, 178,085, 178,086, 178-087, 178,088 and 178,089 filed March 24, 1927. In the embodiment in Fig. I, more in detail, in which one form of type action is shown as applied to a typewriting machine to which it is particularly adapted, 1 indicates the typewriter frame—1^a indicating the front and 1^b the rear. 5 indicates a common platen mounted as usual to travel longitudinally across the rear upper portion of the machine upon a carriage mechanism. As the carriage mechanism forms no part of the present invention, specific disclosure and description thereof is omitted, as its broad function is well known. 6 indicates one of a series of type bars being radially arranged in a curved row about the same center and are movable about their fulcrum pivot rod 9 on a type bar segment 10, Fig. I, from a horizontal or forwardly extending radial position E as the type 7 forms the arc of vibration G and is brought against the front face of platen 5 to a common printing point A. to an upright radial position as shown by radius F. 12 indicates one of a series of key levers carrying at the front end finger key 13, the rear end pivoted at 14 to bar 14^a in the rear of the machine, and is kept normally in its elevated position by the usual spring 15 supported by said bar 14^a, at normal rest the key lever bearing against the underside 15^a of the buffer bar for the key lever 12. 17 indicates a key lever arrestor comprising a bar extending across the machine supporting a series of buffer springs 17^a corresponding in number with the key levers 12. Each buffer spring 17 is coiled about a buffer pin 17^b with a cap head communicating with the under-edge of the key lever, limiting the downward movement of the latter. The extension of the buffer spring 17^a is adjustable by set screw 17^c extending through said bar 17. 18 indicates one of a series of vibratory levers corresponding in number with the type bars 6 and key levers 12 loosely mounted on the rod 14 beside its key lever. The upper end 19 of the vibratory lever 18 is pivoted at 19 to

the rear end of an accelerating linkage comprising a plunger link 20 and a sleeved link 21 with a slid able joint at 21^a and operatively connecting the type bar 6 at 6^a. 22 indicates an accelerating spring coiled about the circumference of the plunger link 20, front end thereof communicating with the rear end of the sleeved link 21 and the rear end of said spring 22 is arrested by a fixed collar 20^a carried by said plunger link 20. A reversely breaking actuating linkage operatively connecting the key lever 12 and vibratory lever, comprise an actuating lever 23, fulcrum trip lever 24 and a roller trip 25. The actuating lever 23 is pivoted at 23^a supported by a bar 26 extending across the machine above the key lever 12 and beneath the fulcrum trip lever 24; the forward arm 23^b provided by said actuating lever 23 operatively connects the key lever 12 at 23^a by a pin and slot connection. The fulcrum trip lever 24 is pivoted at 24^a to the upward end of the actuating lever 23 and is provided with a depending trip arm 24^b communicating with a fulcrum trip bar 23^a, Fig. II, provided by the forward edge of the actuating lever 23 reversely breaking the trip elements after printing impact of the type bar 6 for returning the latter to normal position of rest on cushion 11 while the key lever is held in depressed position as shown in Fig. IV. The rear portion of the fulcrum trip lever 24 is provided with an eyelet 24^c which eyelet engages the angular vibratory lever 18. The roller trip 25 comprises a wheel rotatably about a fixed axle forming the end of said eyelet of the backward portion of the fulcrum trip lever 24. The angular vibratory lever 18 is provided with a saddle backed seat 18^a limiting the downward movement of roller trip 25 and also is provided with an interlocking hump 18^b operatively interlocking the roller trip 25 with said angular vibratory lever for moving the type bar to printing point upon depression of the key lever. The actuating lever 23 is provided with a return bar 23^e at its rear edge communicating with said depending trip arm 24^b of the trip lever 24 for restoring the trip lever and roller trip 25 to normal operative position within the saddle-backed seat 18^a upon release of the key lever as shown in Fig. I. 27 indicates a vertically disposed return spring for returning the angular vibratory lever 18 and plunger link 20 to normal position of rest against a buffer bar 28, said bar extending across the machine in the rear of the latter, limiting the backward movement of the angular vibratory lever 18. The new mechanical structure, combination of parts and operation thereof are the important factors of the invention in providing the desired function of the key action, a further description of the operative principle, therefore, follows:

The key lever 12 is described as having two incidents of operation before completing its operative cycle, namely; the incident of depression and the incident of release. The incident of depression is disclosed by the movement of the key lever 12 from radius B to radius C, and the incident of release is disclosed by the movement of the key lever back from radius C to radius B. The type bar 6 is described as having two incidents of operation before completing its operative cycle, namely; incident of response and incident of recoil. The incident of response of the type bar 6 is disclosed by the movement of the type bar from its initial rest radius E to printing point A, at radius F, forming arc G from pivot 9. The incident of recoil of type bar 6 is disclosed by its movement from the printing point A back to normal rest E thereby completing its operative cycle. These incidents of operation are, of course, common in nonreversely breaking type bar actions in so far as the incident of response, E to A, of the type bar 6 occurs simultaneously with the incident of depression, B to C, of the key lever 12, and the incident of recoil, A to E, of the type bar occurs simultaneously with the incident of release, C to B, of the key lever. In other words, the operative cycle of the type bar and that of the key lever are simultaneous in a nonreversely breaking connection, but the broad function inherent to the present key action relative to the correlation of incidents of operation of the key lever with that of the type bar is in providing the operative expedient by which both the incident of response, E to A, of the type bar and the incident of recoil, A to E, occur during the one incident of depression, B to C, of the key lever, the type bar completing its operative cycle while the operative cycle of the key lever is only half complete. It may be observed that the cycle of movement of the element interpositioned between the key lever and the type bar relative to cycle of movement of the key lever determines the novel action of certain specific elements aside from their novelty of form and other novel features which they might embody. In this case the sleeved link 21 comprising one of the elements of the accelerating linkage has a coacting cycle of movement substantially coincident or simultaneous with the operative cycle of the type bar. The actuating lever 23, fulcrum trip lever 24 and roller trip 25 comprising the system of reversely breaking actuating linkage have a coacting cycle of movement substantially coincident or simultaneous with the operative cycle of the key lever 12. The vibratory lever 18, the plunger link 20 operated by said vibratory lever, and the accelerating spring 22 carried by said plunger link have a coacting cycle of movement independent of the cycle of movement

of the type bar or the cycle of movement of the key lever.

The operative expedient of the present key action is accomplished in this case by a reversely breaking actuating linkage connecting a system of accelerating linkage connecting the type bar and key lever moving the type to printing point upon depression of the key lever, and reversely breaking said actuating linkage alternatively disinterlocking said actuating linkage returning the type bar to normal position while the key lever is in depressed position. Upon depression of the key lever the upward end of the actuating lever 23 moves forwardly carrying with it the horizontally disposed fulcrum trip lever 24 with longitudinal movement the operative relation of the roller trip 25 within the saddle-backed seat 18^a provided by the angular vibratory lever 18 aided by the interlocking hump 18^b operatively interlocks the roller trip 25 with said angular vibratory lever moving the latter forwardly thereby actuating the accelerating linkage forwardly; and upon a quick depression stroke of the key lever the energy of gravity through the weight of the type bar compresses or energizes the accelerating spring 22 providing a resilient or light touch at the beginning of depression of the key lever and as momentum of the key lever increases the energy stored up in said accelerating spring reacts upon the type bar through the slidable link 21 and moves the former toward the printing point. By the time the type bar has arrived at a point on arc G to about radius E_a, Fig. II, the depending trip arm 24^b of the fulcrum trip lever communicates with the forward fulcrum trip bar 23^d provided by the actuating lever 23 and diverts the forward movement of the fulcrum trip lever 24 vibratory upward about its pivot 24^a thereby tripping the roller trip 25 out of operatively interlocked relation with the angular vibratory lever 18, as shown in Fig. III, and the accelerated momentum affected by the accelerating linkage continually moves the type bar from radius E_a to printing point A, radius F, while the angular vibratory lever 18, plunger link 20 and accelerating spring 22 return to normal position completing their cycle of movement before the cycle of movement of the type bar or the cycle of movement of the key lever has been completed.

In a reversely breaking key action it is desirable that means be provided whereby the key lever may have a relatively short depression stroke for actuating a full response stroke of the type bar to printing point. This operative expedient is accomplished in this case in the following manner: Figs. I and IV, disclose that the normal operative position of the forward end of the plunger link 20 extends through and forwardly beyond the sleeved portion of link 21 and remains in this position

until the type bar reaches the point on arc G to about radius Ea as shown in Fig. II, and Fig. III, discloses that the momentum of the type bar continues the movement of the latter to printing point further sliding the sleeved link forwardly on said plunger link 20 thereby operatively elongating the accelerating linkage between the type bar and the vibratory lever 18. The disclosed means of operatively elongating the accelerating linkage connecting the type bar and angular vibratory therefore operates the type bar 6 with about one-fourth of an inch to three-eighths of an inch stroke of finger key 13 contrasted with the usual five-eighths of an inch inherent to a nonreversely breaking key action.

The slideable elongation with its alternatively shortening of the accelerating linkage provides a key action wherein the incident of recoil of the type bar is relatively quicker than the incident of its response in order that the type arc G may be cleared as rapidly as possible when several keys are being manipulated in rapid succession there being no means obstructing the recoil of the type bar after printing impact the printing percussion aided by gravity returns the type bar with efficacious recoil momentum. However, when there is no connecting means to retard the recoil of the type bar, the excessive recoil percussion of the type bar with the cushion rest 11 is also inherent to a reversely breaking actuating coupling. The applicant, therefore, endeavors, in this case, to provide a key action wherein the recoil of the type bar is absorbed by means which substantially neutralizes the recoil percussion of the type bar with the cushion rest 11 in the following manner: Fig. I discloses that the relative normal position of accelerating spring 22 and slideable portion of the sleeved link 21 are communicative and the spring has reached its limit of expansion when the momentum of the type bar has slid the sleeved link 21 away from said spring 22. The spring 22 however, being long enough to function as a buffer spring contacts with the sleeved link 21 and absorbs recoil momentum of the type bar neutralizing the excessive recoil percussion of the latter with said type cushion rest 11.

It is equally important that reliable and rapid means be provided for restoring the elements 24 and 25 of the reversely breaking actuating linkage to normal operative position upon release of the key lever, this being accomplished by the depending trip arm 24^b provided by the fulcrum trip lever 24 communicating with the backward return bur 23^a provided by the actuating lever 23, actuating the rear end of the fulcrum trip lever 24 downwardly thereby restoring the roller trip 25 and angular vibratory lever 18 to normal operative interlocked position.

In a reversely breaking key action when operating a certain type bar in rapid suc-

sion, as when printing double letters in a word, it is desirable that the reversely breaking connection between the key lever and type bar reversely break and in turn operatively interlock before the type bar has returned to its normal position in order that when the key 13 is depressed part way down in rapid succession, the type bar will move to printing point A and only partly return on arc G to about radius Ea Fig. I, and alternatively impact and recoil within the radii of F—Ea. This operative expedient is accomplished by the angular vibratory lever 18 having a coacting cycle of movement with the plunger link 20 and accelerating spring 22 substantially independent of the cycle of the movement of the type bar or key lever. The relative instant of operation of the actuating elements is predetermined or timed in order that the roller trip 25 may be tripped out of the saddle-backed seat 18^a about the time the type bar 6 responds to radius Ea, Fig. II, and while the type bar 6 continues to move under the influence of momentum from radius Ea to radius F the vibratory lever 18, plunger link 20, and accelerating spring 22 return to normal position of rest as shown by Fig. III before the type bar 6 has reached the printing point A; hence the key lever may be released immediately after the type bar 6 has reached a point on arc G to about radius Ea again interlock the trip elements 18^a and 25 about the time the type has reached the printing point and begins to recoil, and while the type bar returns from radius F to radius Ea the key lever 12 may again be moving from radius B to radius C and the depression energy of the key lever again overcoming the recoil energy of the type bar on the return of the latter to about radius Ea Fig. II. At this stage of operation the accelerating spring 22 absorbs the opposing forces of the depression of the key lever and recoil of the type bar again responds the latter from Ea to F with efficacious impact.

Inherent to a reversely breaking key action when the elements reversely break before the key lever has reached the limit of its downward movement the latter has a tendency to "drop" effecting an uneven touch during the depression of the key lever. This exigency is ameliorated in this case by a key lever arrester 17, the mechanism of which is hereinbefore described. Fig. I discloses a disconnection between the key lever and buffer pin head 17^b. Upon depression of the key lever the latter moves downwardly and communicates with the buffer pin head 17^b at the time predetermined that the depending trip arm 24^b communicates with the trip bur 23^a, as shown in Fig. II, the buffer spring 17^a simultaneously absorbing the depression energy of the key lever released when the elements reversely break, thereby effecting a uniform depression movement of the key lever.

Finally, it will be seen that the present invention provides a simple and practical type action which will be rapid and efficient in use, accomplishing, among others, all of the 5 objects and advantages above set forth, therefore the operation and method of use of a type action of this character is believed to be perfectly clear from the above description, a reiteration thereof is believed to be 10 unnecessary. As many changes could be made in the above construction and many apparently widely different embodiments of this invention could be made without departing from the scope thereof it is intended that 15 all matter contained in the above description, or shown in the accompanying drawings, shall be interpreted as illustrative and not in a limiting sense, and variations may be resorted to within the scope of the invention, 20 and portions of the improvement may be used without others.

Having described my invention, what I claim as new and desire to secure by Letters Patent is:

25 1. In a typewriter key action, a type bar, a key lever, a pivot rod for the rear end of said key lever, an angular vibratory lever loosely mounted on said key lever pivot rod beside its key lever, an accelerating linkage operatively connecting the type bar and vibratory lever, a reversely breaking actuating connection operatively connecting the key lever and vibratory lever moving the type bar to printing point upon depression of the key lever, means reversely breaking said connection after 35 printing impact of the type bar for returning the type bar to normal position while the key lever is in depressed position.

40 2. In a typewriter key action, a type bar, a key lever, a pivotal rod for the rear end of said key lever, an angular vibratory lever loosely mounted on said key lever pivotal rod beside its key lever, an accelerating linkage operatively connecting the type bar and vibratory lever, a reversely breaking actuating connection operatively connecting the key lever and vibratory lever moving the type bar to printing point upon depression of the key lever, means reversely breaking said connection after 45 printing impact of the type bar for returning the type bar to normal position while the key lever is in depressed position, means restoring said reversely breaking actuating connection to normal operative position upon release of the key lever.

55 3. In a type key action, a type bar, a key lever, a pivot rod for the rear end of said key lever, an angular vibratory lever loosely mounted on said key lever pivot rod beside its key lever, an accelerating linkage operatively connecting the type bar and vibratory lever, a reversely breaking actuating connection comprising an actuating lever, a fulcrum trip lever and a roller trip operatively connecting the key lever and vibratory lever

60 moving the type bar to printing point upon depression of the key lever, means reversely breaking said connection after printing impact of the type bar for returning the type bar to normal position while the key lever is in depressed position.

65 4. In a type key action, a type bar, a key lever, a pivotal rod for the rear end of said key lever, an angular vibratory lever loosely mounted on said key lever pivotal rod beside its key lever, an accelerating linkage operatively connecting the type bar and vibratory lever, a reversely breaking actuating connection comprising an actuating lever, a fulcrum trip lever and a roller trip operatively connecting the key lever and vibratory lever moving the type bar to printing point upon depression of the key lever, means reversely breaking said connection after printing impact of the type bar for returning the type bar to normal position while the key lever is in depressed position, 70 means restoring said reversely breaking actuating connection to normal operative position upon release of the key lever.

75 5. In a type key action, a type bar, a key lever, a pivotal rod for the rear end of said key lever, an angular vibratory lever loosely mounted on said key lever pivotal rod beside its key lever, an accelerating linkage comprising a plunger link, a sleeved link including an accelerating spring about the circumference of said plunger link operatively connecting the type bar and vibratory lever, a reversely breaking actuating connection operatively connecting the key lever and vibratory lever moving the type bar to printing point upon depression of the key lever, means reversely breaking said connection after 80 printing impact of the type bar for returning the type bar to normal position while the key lever is in depressed position.

85 6. In a typewriter key action, a type bar, a key lever, a pivotal rod for the rear end of said key lever, an angular vibratory lever loosely mounted on said key lever pivot rod beside its key lever, an accelerating linkage comprising a plunger link, a sleeved link including an accelerating spring coiled about the circumference of said plunger link operatively connecting the type bar and vibratory lever, a reversely breaking actuating connection comprising an actuating lever, a fulcrum trip lever and a roller trip operatively connecting the key lever and vibratory

90 100 105 110 115 120 125 130

lever moving the type bar to printing point upon depression of the key lever, means reversely breaking said connection after printing impact of the type bar for returning the type bar to normal position while the key lever is in depressed position.

130 7. In a typewriting machine, a type bar, a key lever, a pivotal rod for the rear end of said key lever, an angular vibratory lever loosely mounted on said key lever pivotal rod

beside its key lever, an accelerating linkage comprising a plunger link, a sleeved link including an accelerating spring coiled about the circumference of said plunger link operatively connecting the type bar and vibratory lever, a reversely breaking actuating connection comprising an actuating lever, a fulcrum trip lever and roller trip operatively connecting the key lever and vibratory lever 5 moving the type bar to printing point upon depression of the key lever, means reversely breaking said actuating connection after printing impact of the type bar, for returning the type bar to normal position while the key lever is in depressed position, means restoring said reversely breaking actuating connection to normal operative position upon release of the key lever.

8. In a typewriting machine, a type bar, a key lever, a pivotal rod for the rear end of 20 said key lever, an angular vibratory lever loosely mounted on said key lever pivotal rod beside its key lever, an accelerating linkage comprising a plunger link, a sleeved link including an accelerating spring coiled about the circumference of said plunger link operatively connecting the type bar and vibratory lever, a reversely breaking actuating connection operatively connecting the key lever and vibratory lever moving the type bar 25 to printing point upon depression of the key lever means reversely breaking said connection after printing impact of the type bar for returning the type bar to normal position 30 while the key lever is in depressed position, means restoring said reversely breaking actuating connection to normal operative position upon release of the key lever.

9. In a type key action, a type bar, a key lever, a pivotal rod for the rear end of said key lever, an angular vibratory lever loosely mounted on said key lever pivotal rod beside its key lever, an accelerating linkage operatively connecting the type bar and vibratory lever, a rearwardly extending arm intermediate of said vibratory lever providing a saddle-backed seat, a reversely breaking actuating connection comprising an actuating lever, a fulcrum trip lever, and a roller trip operatively connecting the key lever and vibratory lever, an interlocking hump provided by the angular vibratory lever operatively interlocking the roller trip within said saddle-backed seat of the angular vibratory lever moving the type bar to printing point upon depression of the key lever, means tripping the roller trip out of operative interlocked position within said saddle-backed seat reversely breaking said connection after 45 printing impact of the type bar for returning the type bar to normal position while the key lever is in depressed position, means restoring the trip lever and roller trip to normal operative position within said saddle-backed seat upon release of the key lever.

10. In a typewriting machine, a type bar, a key lever, a pivot rod for the rear end of said key lever, an angular vibratory lever loosely mounted on said key lever pivot rod beside its key lever, a reversely breaking actuating connection operatively connecting the type bar and vibratory lever, an accelerating linkage comprising a plunger link operatively connecting the vibratory lever, an accelerating spring coiled about said plunger link, a fixed collar carried by the plunger link arresting the rear end of said accelerating spring, a sleeved link, the rear portion thereof providing a sleeve slidable about the forward end of said plunger link forming a slidable joint operatively connecting the plunger link and sleeved link, the rear end of said sleeve communicating with the forward end of said accelerating spring and the forward end of said sleeved link operatively connecting the type bar moving the type bar to printing point upon depression of the key lever, means reversely breaking said actuating connection after printing impact of the type bar for returning the type bar to normal position while the key lever is in depressed position, means restoring said reversely breaking actuating connection to normal operative position upon release of the key lever.

11. In a typewriting machine, a type bar, a key lever, a pivot rod for the rear end of said key lever, an angular vibratory lever loosely mounted on said key lever pivot rod beside its key lever, a reversely breaking actuating connection operatively connecting the key lever and vibratory lever, an accelerating linkage comprising a sleeved link, a plunger link, the forward end thereof slideable through said sleeved link, an accelerating spring coiled about said plunger link, a fixed collar carried by said plunger link arresting the rear end of said spring, the forward end of said spring contacting with the sleeved link accelerating the movement of the type bar to printing point upon depression of the key lever, means reversely breaking said actuating connection after printing impact of the type bar for returning the type bar to normal position while the key lever is in depressed position, said spring absorbing the recoil momentum of the type bar neutralizing the excessive recoil percussion of the latter with said type cushion rest, means restoring said reversely breaking actuating connection to normal operative position upon release of the key lever.

12. In a typewriter machine, a type bar, a key lever, a pivot rod for the rear end of said key lever, an angular vibratory lever loosely mounted on said key lever pivot rod beside its key lever, a reversely breaking actuating connection operatively connecting the key lever and vibratory lever, an accelerating linkage operatively connecting the

- type bar and vibratory lever comprising a 5
slidable link and a plunger link with its rear
end connecting to the upper end of the vibratory
lever, a slidable joint connecting the forward
end of the plunger link with the rear
end of the sleeve link for alternatively elongating
and shortening said accelerating linkage,
a fixed collar carried by said plunger link,
an accelerating spring coiled about said
plunger link between said fixed collar and
sleeved link limiting the shortening of said
accelerating linkage accelerating the movement
of the type bar to printing point upon
depression of the key lever, means reversely
breaking said actuating connection after
printing of the type bar for returning the
type bar to normal position while the key
lever is in depressed position, means restoring
said reversely breaking actuating connection
to normal operative position upon
release of the key lever. 10
13. In a type key action, a type bar, a key
lever, a pivot rod for the rear end of said key
lever, an angular vibratory lever loosely
25 mounted on said key lever pivot rod beside its
key lever, an accelerating linkage operatively
connecting the key lever and vibratory lever,
a reversely breaking actuating connection
comprising a fulcrum trip lever, a
30 depending arm provided by said fulcrum
trip lever, a roller trip operatively inter-
locking said vibratory lever, an actuating
lever, a bar extending across the machine
above the key lever pivotally supporting
35 said actuating lever, a forward arm pro-
vided by said actuating lever operatively
connecting the key lever by a pin and slot
connection moving the type bar to print-
ing point upon depression of the key lever,
40 a fulcrum trip bur provided by the for-
ward edge of said actuating lever communi-
cating with the fulcrum trip lever arm re-
versely breaking said actuating connection
after printing impact of the type bar for
45 returning the type bar to normal position
while the key lever is in depressed position, a
return bur provided by the rear edge of said
actuating lever communicating with the rear
edge of the fulcrum trip lever arm restoring
50 said reversely breaking actuating connection
to normal operative position upon release of
the key lever. 110
14. In a key action for a typewriting ma-
chine a type bar, a key lever, a pivot rod for
55 the rear end of said key lever, an angular vi-
bratory lever loosely mounted on said key le-
ver pivot rod beside its key lever, an acceler-
ating linkage operatively connecting the type
bar and vibratory lever, a reversely breaking
60 actuating connection comprising an actua-
ting lever provided with a fulcrum trip bur
and return bur at its forward and rear
edges operated by the key lever, a fulcrum
trip lever pivotally operated by said actua-
65 ting lever, a depending trip arm provided
by said fulcrum trip lever, an eyelet pro-
vided by the rear portion of the fulcrum
trip lever engaging about said angular vi-
bratory lever, a roller trip comprising a
70 wheel rotatable about an axle forming the
rear end of said eyelet moving the type bar to
printing point upon depression of the key
lever, said fulcrum trip lever arm communi-
cating with the fulcrum trip bur reversely
75 breaking said actuating connection after
printing impact of the type bar for returning
the type bar to normal position while the
key lever is in depressed position, said ful-
crum trip lever arm communicating with the
80 return bur restoring said reversely breaking
actuating connection to normal operative po-
sition upon release of the key lever. 85
15. In a type key action, a type bar, a key
lever, a pivot rod for the rear end of said key
lever, an angular vibratory lever loosely
90 mounted on said key lever pivot rod beside its
key lever, an accelerating linkage operatively
connecting the type bar and vibratory lever,
a reversely breaking actuating connection
operatively connecting the key lever and vi-
95 bratory lever moving the type bar to printing
point upon depression of the key lever, means
reversely breaking said actuating connection
after printing impact of the type bar for re-
turning the type bar to normal position while
100 the key lever is in depressed position, a key
lever arrestor comprising a bar extending
across the machine supporting a series of
buffer springs corresponding in number with
the key levers, a series of set screws corre-
105 sponding in number with the buffer springs
extending partly through said buffer bar
each supporting one of said springs, a loose
pin within the coils of said spring, a stop
head provided by said pin predeterminedly
110 communicating with the underside of the
key lever at the time said reversely breaking
actuating connection reversely breaks ab-
sorbing the depression energy of the key
lever effecting a uniform depression move-
ment of the key lever, means restoring said
115 reversely breaking actuating connection to
normal operative position upon release of the
key lever. 120
16. In a key action for a typewriting ma-
chine, a type bar, a key lever, a pivot rod for
the rear end of said key lever, an angular vi-
bratory lever loosely mounted on said key le-
ver pivot rod beside its key lever, a reverse-
125 ly breaking actuating connection operatively
connecting the key lever and vibratory lever,
an accelerating linkage operatively connect-
ing the key lever and vibratory lever moving
the type bar to printing point upon a rela-
tively short depression stroke of the key le-
ver, means reversely breaking said actuating
connection before printing impact of the
type bar, a buffer bar extending across the
130 machine in the rear of the latter communi-
cating with and limiting the backward move-

ment of said vibratory lever, a vertically disposed return spring supported by a bar extending across the rear of the machine, the upper end of said spring operatively connecting the vibratory lever for returning the vibratory lever to normal position of rest against said buffer bar before the type bar returns to normal position while the key lever is in depressed position, means restoring said 10 reversely breaking actuating connection to normal operative position upon release of the key lever.

17. In a key action, a type bar, a key lever, a sleeved link operatively connecting the type bar having a coacting cycle of movement substantially coincident with the operative cycle of said type bar; a vibratory lever, a plunger link operated by said vibratory lever and operatively connected to the 20 sleeved link and an accelerating spring carried by said plunger link having a coacting cycle of movement substantially independent of the cycle of movement of the type bar or the cycle of movement of the key lever; a system of reversely breaking actuating linkage 25 operatively connecting the key lever and vibratory lever comprising an actuating lever, a fulcrum trip lever and a roller trip having a coacting cycle of movement substantially coincident with the operative cycle of the key lever, a coacting half-cycle of movement of the actuating lever, fulcrum trip lever, vibratory lever, plunger link, accelerating spring and sleeved link moving the type bar 30 to printing point upon depression of the key lever, means reversely breaking said system of actuating linkage returning said vibratory lever, plunger link and accelerating spring to normal position completing their cycle 35 of movement independently of the cycle of movement of the type bar and returning the type bar to normal position completing its cycle of movement while the key lever is in depressed position; means restoring the actuating lever, fulcrum trip lever and roller trip 40 to normal operative position completing their cycle of movement upon release of the key lever.

18. In a type key action, a type bar, a key lever, a pivot rod for the rear end of said key lever, an angular vibratory lever loosely mounted on said key lever pivot rod beside its key lever, a reversely breaking actuating connection operatively connecting the key lever 50 and vibratory lever, an accelerating linkage comprising a plunger link, a sleeved link including an accelerating spring coiled about the circumference of said plunger link, slideable means connecting the plunger link and 55 slideable sleeve operatively elongating the accelerating linkage actuating a full response stroke of the type bar to printing point upon 60 a relatively short depression stroke of the key lever, means reversely breaking said 65 actuating connection after printing impact

of the type bar for returning the type bar to normal position shortening the accelerating linkage connecting the type bar and vibratory lever while the key lever is in depressed position, means restoring said 70 reversely breaking actuating connection to normal operative position upon release of the key lever.

Signed at Fort Collins, in the county of Larimer and State of Colorado, this 24th day of Jan. A. D. 1928.
